CAN OPENING AND SPOUT FORMING
DEVICE

Herbert A. Johnston, Anaheim, Calif.

Application August 16, 1938, Serial No. 225,133

5 Claims. (Cl. 30—8)

This invention relates to improvements in can opening and spout forming devices.

The general object of my invention is to provide a novel improved can opener.

5 Another object of the invention is to provide a novel can opener which includes a novel punching and spout forming device particularly adapted for use with cans containing fluids such as fruit juices, condensed milk, oil, etc.

10 Another object of the invention is to provide a novel can opener having a number of punching members adapted to produce apertures of various sizes in a can.

15 Another object of the invention is to provide a novel can opener including novel means to prevent the removed can top from falling into the can.

20 Other objects and advantages of my invention will be apparent from the following description taken in connection with the accompanying drawing, wherein:

25 Fig. 1 is a side elevation of a can opener and spout forming device embodying the features of my invention with parts broken away to show the interior construction;

Fig. 2 is a top plan view of the device with parts broken away to show the interior construction;

30 Fig. 3 is a fragmentary enlarged front view taken along the axis of the rotating multiple piercing device;

Fig. 4 is an enlarged fragmentary vertical section of a can with the top punched and a spout formed;

35 Fig. 5 is a fragmentary enlarged top plan view of a can with top punched and a spout formed;

Fig. 6 is an enlarged fragmentary vertical section through a can showing the top being removed and held from dropping within the can;

40 Fig. 7 is a section taken on line 7—7 of Fig. 1;

Fig. 8 is a side elevation showing the cutter; and

Fig. 9 is a section taken on line 9—9 of Fig. 8.

Referring to the drawing by reference characters I have shown my invention as embodied in a can opening and spout forming device which is indicated generally at 10. As shown in Figs. 1 and 2 the device is shown in use with an ordinary can 11 having a body portion 12 and a top 13 joined by the usual seam 14.

The main parts of the opener 10 are preferably light die castings or stampings and as shown the opener includes two hollow handles 15 and 16 pivoted together by the pin 17 and each having

55 grip portions 15' and 16', respectively, adapted

to be engaged by the hand of the operator. The handle 15 is somewhat wider than the handle 16 and has an aperture 18 near the pivotal point through which the handle 16 extends. A spring 19 passes around the pin 17 and engages the handles 15 and 16 normally urging them apart.

At the end remote from the hand engaging portion 15' the handle 15 is bifurcated forming two arms 20 and 21. Rigidly connected to the free end of the arm 20 is a pin 22 having a wheel 23 pivotally mounted thereon. The free end of the arm 21 carries a shaft 24 with a wheel 25 rigidly mounted on one end thereof. The periphery of the wheel 25 is provided with teeth 26 adapted to engage the underside of the seam 14 15 of the can 12. It will be seen that the axes of the wheels 23 and 25 are coplanar and are approximately radial with respect to the axis of the can 12.

On the handle 15 near the pivotal point I provide a bracket 27 which is held in place by suitable means such as rivets 28. The shaft 24 extends through the bracket 27 as at 29 and 30. The shaft 24 has a crank portion 35 terminating in a knob 36.

At the end remote from the hand engaging portion 16' the handle 16 is provided with a pin 37 which is rigidly mounted thereon. Pivotally mounted on the pin 37 is a multiple piercing device 38 including a plurality of integral punch members 39 and a cutter 40 arranged radially as shown in Fig. 3.

Each of the punch members 39 has a plane front face 41 and a curved rear portion 42 as shown in Fig. 7. The outer end of each punch member 39 terminates in two bevelled cutting edges 43 and 44 at substantially right angles to each other forming a sharpened point 45 at the juncture of these two edges.

The multiple piercing device includes a radial arm 47 which has a slot 48 therein which receives the cutter 40 previously mentioned. The cutter 40 includes a flat portion 49 which in use engages the top 13 of the can 11, and an inclined cutting edge 50. The cutter 40 has a bent portion 51 at the free end, the crease being sharpened as at 52. Mounted on the arm 47 is a leaf spring 53 which in use engages the top 13 of the can 11 pressing the top against the bent portion 51.

The spring 53 is attached by a rivet 53' 50 which may also be used to fasten the cutter 40 in the slot 48. Slidably mounted in a suitable fixture 54 positioned on the handle 16 adjacent the multiple piercing device 38 I provide a pin 55 which has an enlarged head 56 adapted to 55

engage an aperture 57 in each of the punch members 39 and the cutter arm 48 thus holding the assembly 38 in locked position. A spring 58 surrounding the pin 55 engages the fixture 54 and urges the head 56 forward. The pin 55 is bent upwardly and flattened as at 58' for finger engagement.

Within a recess in the handle portion 15' I provide a corkscrew 60 mounted on a pin 61 as shown in Figs. 1 and 2. A bottle cap remover of the usual type 62 has a base 63 secured to the handle 15.

When it is desired to punch a can containing fluid, the desired punch member is rotated into position and locked by the pin 55. For convenience different sized punches are provided, it being desirable for instance to provide a larger aperture in a can of oil than in a can of condensed milk. The wheels 23 and 25 are placed beneath the seam 14 of the can 11 and the handles 15 and 16 urged together by the operator. The sharpened point 45 pierces the top 13 and further movement enlarges the aperture while still further movement by forcing the seam 14 and body portion 12 between the arms 20 and 21 form the material into a spout shape as shown in Figs. 4 and 5.

When it is desired to remove the entire top from a can the cutter 40 is revolved to the downward position, the wheels 23 and 25 positioned below the seam 14, and the handles 15 and 16 are brought together forcing the blade 46 into the top 13 of the can 11 so that the bent portion 51 is entirely below the top 13 and the flat portion 49 lies above the top 12. The crank 35 is then actuated to thereby revolve the can 11 by engagement with the toothed wheel 25. As shown in Fig. 6 the top 13 during this operation is engaged by the bent portion 51 and the spring 53 so that when the top is entirely severed it will be prevented from falling within the can and is removed with the opener.

From the foregoing description it will be apparent that I have invented a novel can opening and spout forming device.

Having thus described my invention I claim:

1. In a can opening device, a pair of pivoted handles, a pair of spaced wheels on one of the handles, the axes of said wheels being coplanar and approximately radial with respect to the can,

said wheels being adapted to engage the rim of a can and to move therearound, and a piercing member pivotally mounted on the other handle, said piercing member including a can cutting element.

2. A can opener comprising a body having a toothed wheel and having cutting means adapted to cut the top from a can, means to rotate said toothed wheel, said cutting means including a blade having a cutting portion and a part adapted to engage the under surface of a can lid and spring means on the cutting member adapted to engage the upper surface of a can lid opposite to the portion engaged by the cutting portion.

3. In a can opening device, a pair of pivoted handles, means on one of said handles adapted to engage a can, means to move the can engaging means about a can, a cutter member mounted on the other arm, said cutter member including a cutting element having a lid engaging portion adapted to be disposed beneath a lid being cut and resilient means on the cutter member to urge a can lid against the lid engaging portion of the cutting element whereby the lid may be removed after it is severed.

4. In a can opening and spout forming device, a pair of pivoted handles, one of said handles having a pair of arms at one end, can engaging means on each of said arms, means to move said can engaging means about the can, a can opening member on said other handle, said member having an inclined blade with a bent portion which is upwardly directed and adapted to be disposed beneath the top of a can and spring means adjacent said blade member adapted to engage the top of a can.

5. In a can opening and spout forming device, a pair of pivoted handles, one of said handles having a pair of spaced arms at one end, a wheel pivotally mounted on each of said arms, one of said wheels having peripheral teeth thereon, manual means to rotate said toothed wheel, said wheels being adapted to engage the underside of a can seam, the axes of said wheels being coplanar and approximately radial with respect to the can, a pin rigidly mounted on the outer end of the other handle, a cutting member pivotally positioned on said pin, said cutter member being shiftable to engage a can.

HERBERT A. JOHNSTON. 50
